UNITED STATES PATENT OFFICE.

JOHN PERCY, OF ALBANY, NEW YORK.

IMPROVEMENT IN WATER-METERS.

Specification forming part of Letters Patent No. 37,588, dated February 3, 1863.

To all whom it may concern:

Be it known that I, JOHN PERCY, of the city of Albany, and State of New York, have invented a new and Improved Water-Meter, or Machine for Registering Water or the Quantity of Water that is Drawn or Passed Through the Same; and I hereby declare that the following is a full and exact description of the same, reference being had to the accompanying drawings and the letters and figures of reference marked thereon.

Figure 1 represents a front elevation of the water-meter with a portion of the casing removed. Fig. 2 is a transverse section of the same. Fig. 3 is a longitudinal section. Fig. 4 is a plan in section. Fig. 5 is a perspective view of valve-box with valve. In all the figures, similar letters denote the same parts of the apparatus.

My machine is constructed as follows:

A A is the outer wall or casing that surrounds the water-tight parts of the meter.

B, Fig. 3, is a horizontal partition extending across the meter, dividing it into two parts, water-tight, and preventing the water from passing downward in any other way than through the cylinders F and G, whose open upper mouths are closely fitted into the partition.

C is a perpendicular partition extending from the center of partition B up to the floor of a valve-chamber or square box, P, that contains the supply-valves. It divides the upper chamber of the meter into independent compartments, D and E. The cylinders F and G are provided with movable pistons H for F and J for G. Each of these pistons is provided with a large discharge-valve opening upward, (formed as shown by the drawings.)

I is the valve in piston H, and K in piston J. These pistons are attached to the ends of a walking beam or lever, L, which vibrates on shaft *l*, its hub fitted into the partition C, and has forked ends *e e f f*, Fig. 4, from which it is connected with the piston by rods *i i i i*, attached one on each side of the valve.

M is another walking beam or lever vibrating on shaft *m*, its hub also fitting into partition C, so that its hub and the hub of L may roll or rub on each other to form a tight joint. The outer edge of these hubs, as well as their sides, is fitted to rub as snugly as is consistent with free motion against the edge of the

slot in C, through which they pass. Each end of M is connected with a valve in the piston by a rod, W, extending down between the forked ends *e f* of lever L. The beam M is provided with two arms projecting upward, on the upper ends of which are valves N and O, that present their faces toward openings *n o*, which pass the water out from the valve-chamber, P. As these valves come in contact with the said openings they alternately check the valves I and K—that is to say, the valve-rod W, attached to beam M in its upward progress, is stayed by said contact until the piston J on beam L is raised upward and closes valve K in piston J, and the opposite end of beam L is depressed and opens valve I in piston H, and so of the opposite in reverse. This valve-chamber P is a square box placed in the top of the meter, with side walls, *a a'*, and end walls, *b b'*, extending from the back to the front plate of the meter, and from its top to a bottom plate lying on the top of partition C, its back and front walls, *a a'* closing the space between the end walls, leaving narrow chambers R and S between *a a'* and the back and front walls of the meter. Against the inner faces of *a a'* are placed rotating valves *v v'*. These are disks (see Figs. 3 and 5) of metal, having openings triangularly shaped cut through them, leaving between them the metal of similar form and occupying a little more surface than the openings do. They are ground or fitted to the inner faces of *a a'*, against which they move, and which have similar openings to those of the valves, so that in one position the metal of the valves covers the openings, in another uncovers them, (the arrangement being like that commonly used for hot-air registers and ventilators.) The valves are fixed upon the common shaft T, running through their centers. They are adjusted in reference to each other, so that while the valve V closes the opening in *a*, *v'* shall uncover its opening in *a'*. The valves being immovable upon the shaft T, and the flow of water being from the center outward the pressure on the one valve balances that of the other, so that a very slight power will operate them. The water that passes from the valve-chamber into chamber R has an exit-passage at *n*, that into chamber S at *O*, these passages being made through the walls *b b'*. The valve-shaft T, Fig. 2, projects beyond the

front wall, A, of the meter by a water-tight joint, and is made to carry a hanging double-jawed lever V, fixed upon the shaft, each of the jaws having at its lowest point a pin, 6 and 7, projecting from it. Catches or detents 1 and 2, Fig. 1, are pivoted to the front plate, A, of the meter, arranged, as shown in the drawings, to catch and hold the lever U by its pins 6 and 7 whenever pressed to either side within their reach. A cross-bar, 3, is secured to the outer end of the shaft l, Fig. 3, which passes through a water-tight joint in the wall A of the meter, and has two tripping-rods, 4 and 5, one at each end, reaching upward and nearly to the catches 1 and 2, upon which they are to operate.

W is a spring firmly secured to the cross-bar 3, or its shaft F, so as to move by the vibration of the beam L. The spring reaches up so as to operate with the pins and detent, as hereinafter described. In addition to this, to the outer end of the shaft l there is attached an escapement-movement consisting of an anchor-lever, X and toothed wheel Y, whose object is, by the vibration of lever L, to operate a connecting train of wheel-work, Z, with dials to register the amount of water passing through the machine. Between the cylinders F G is a chamber or reservoir, 10, into which the lower part of the cylinders open by valves 8 and 9, whence it passes out through the stop-cock 11 for use.

The operation of the machine is thus; In the position shown in the drawings it is at a stand, the cock 8 being shut. The reservoir 10, cylinder G, and chamber E, chamber S, valve chamber P are full of water, and the valve V opens, the supply of water being open to the machine through pipes Q. The moment the cock 8 is opened the pressure of water through valve V presses down the piston J, its valve K being closed till it reaches near the bottom of the cylinder, the water underneath it escaping by the valve 9. In the meanwhile the piston H, with its open valve I, ascends *pari passu* with K until the valve N closes the opening n of the compartment R. At the same time the cross-bar 3, by the move-

ment of shaft l of beam L, has lifted rod 4, so that at the instant valve N closes n the detent 1 is tripped, and spring W, suddenly striking the pin on the opposite jaw of V, drives it up with itself under detent 2, shutting instantly valve V and opening V'. A rush of water now projects itself against N, drives it down, and closes valve I on piston H, and opens valve K in piston J. Then the water filling chamber D forces piston H down to the bottom of the cylinder. While the chamber D and cylinder F are filling the water which had filled chamber E and cylinder G passes through open valve K, out of valve 7, into chamber Y, and out at cock 8. When by this movement valve O closes upon opening o, the detent 2 is tripped by the action of the cross-bar 3 and the valve v and v' again shifted, and the operation of the machine repeated in reverse. Each change of movement discharges the contents of the chamber and cylinder, and no more, which is registered by the movements of the escapement-dials at Z.

What I claim, and desire to secure by Letters Patent as my invention, is—

1. A balance-valve as constructed, for the purpose described.

2. The arrangement and combination substantially in the manner and for the purpose set forth in the above specifications of the following apparatus, viz: the valve-chamber P, with its valves v and v and stem T, the chamber D and E, the cylinders F and G, with their pistons H and J, connected with beam L, the valve I and K, connected with beam M, the valve N and o, also connected with beam M o, operating valves I and K, the lever U, attached to valve-shaft T, the detents 1 and 2, with their pins 6 and 7, lever 3, attached to shaft of beam M, with the tripping-levers 4 and 5, spring W, operated by beam M, in order to operate lever v, the lever X, as connected with apparatus measuring the water, forming together a complete water-meter.
